UNITED STATES PATENT OFFICE.

LOUIS V. ARONSON, OF NEWARK, NEW JERSEY.

DESIGN FOR A CLOCK-CASE.

SPECIFICATION forming part of Design No. 35,796, dated March 11, 1902.

Application filed February 11, 1902. Serial No. 93,630. Term of patent 3½ years.

To all whom it may concern:

Be it known that I, LOUIS V. ARONSON, a citizen of the United States, residing at Newark, in the county of Essex and State of New Jersey, have invented and produced a new and original Design for a Clock-Case, of which the following is a specification, reference being had to the accompanying drawings, forming a part thereof.

Figure 1 is a front elevation of a clock-case embodying my new design. Fig. 2 is a side view of the same.

As shown in the accompanying drawings, the leading or material features of my design are the die or pedestal, its ornamental base with scroll feet, the female figure, and the spray of foliage surmounted by the socket for the clock.

This design comprises a die or pedestal *a*, having a molded base *b*, with scroll-feet *c* at its corners, a spray of foliage *d*, projected upward from the base adjacent to one side of

the pedestal, the socket *f* for the clock, supported upon such foliage and having the foliage extended around the socket and terminated in a scroll above the top of the same, and a female figure *e*, standing upon the pedestal *a*, with the arms of the figure extended toward the scroll of the socket and one hand leaning against the cheek of the figure. The female figure *e* is draped quite loosely, and the whole design is in the baroque style of the fifteenth century.

Having thus described my invention, what I claim is—

The design for a clock-case as herein shown and described.

Signed at Newark, in the county of Essex and State of New Jersey, this 3d day of February, 1902.

LOUIS V. ARONSON.
